UNITED STATES PATENT OFFICE.

J. FRANK ALLARD, OF BOSTON, MASSACHUSETTS, ASSIGNOR, BY MESNE ASSIGNMENTS, TO UNDERWOOD TYPEWRITER COMPANY, OF NEW YORK, N. Y., A CORPORATION OF NEW JERSEY.

TABULATING-STOP FOR TYPE-WRITERS.

No. 918,722.

Specification of Letters Patent. Patented April 20, 1909.

Application filed March 3, 1899. Serial No. 707,567.

To all whom it may concern:

Be it known that I, J. FRANK ALLARD, of Boston, in the county of Suffolk and State of Massachusetts, have invented certain new and useful Improvements in Tabulating-Stops for Type-Writers, of which the following is a description sufficiently full, clear, and exact to enable those skilled in the art to which it appertains or with which it is most nearly connected to make and use the same.

This invention relates to devices for effecting the shifting and stopping the carriage of a typewriter at any predetermined point for securing exact vertical alinement of figures or words, as is necessary in the writing of tables, bills, and other kinds of schedule work.

The invention has for its main object the provision of a single key which may be readily and quickly operated to effect a release or shift the carriage and stop it at any point or denomination in a column of figures, without using the space bar or regular carriage-releasing means, and without being under the necessity of observing anything else than the movement of the said single tabulating key.

To these ends the invention consists broadly of a depressible and laterally-movable tabulating key lever which operates to shift and adjust the rocking and laterally-movable tabulating stop-rod so as to bring the stops to any desired point and also to release the carriage so that it may be stopped by an adjusted stop on the rod or by other means, all as I will now proceed to describe in detail and subsequently point out with particularity in the appended claims.

Reference is to be had to the annexed drawings and to the letters marked thereon forming a part of this specification, the same letters designating the same parts or features, as the case may be, wherever they occur.

Of the drawings—Figure 1 is a perspective view of my invention and parts with which it is immediately connected and operates, portions being shown as broken away in order to more clearly show particular parts and features. Fig. 2 is a plan view of the same, portions being shown in section. Fig. 3 is an end view of the same. Fig. 4 is a perspective view of the column stop forming part of the mechanism and Fig. 5 is an end view of said stop with parts broken away.

In the drawings—*a* designates the machine frame.

b is the stop-rod or bar provided with holes *c* formed longitudinally therein from its ends into which journal pins *d d* extend from the frame, so that the said bar *b* may be both rocked and moved longitudinally on said journals.

At one end (the right-hand end, as the invention is herein represented) the stop bar and journal pin are surrounded by a sleeve *e*, and a helical spring *f* connected at one end to the frame *a* and at the other to the stop-bar surrounds the said sleeve and bar and operates to return the latter device to normal position when rocked and shifted longitudinally by the tabulating lever, as will be presently explained. The sleeve is provided at its outer end with a flange through which it is secured to the frame by means of screws *g*.

Supported by the upper ends of brackets *h h* connected at their lower ends with the stop-rod is a bar *i* having a scale inscribed thereon corresponding to the cylinder scale (not shown) in front of the machine so that stops *j* on the stop-bar *b* may be set thereon with certainty with respect to the cylinder scale, a pointer *k* extending up from the stop *j* to and over the scale-bar *i* to indicate the position of the stop relatively to the cylinder scale. The stops *j* are maintained in "set" position on the stop-bar *b* by teeth thereof engaging with the teeth formed on said bar.

l designates a short bar secured to the frame *a* and provided in its upper side with teeth adapted to be engaged by a finger *m*, projecting forward from a bracket *h*, when the stop-bar and its equipments are rocked forward, as will be hereinafter explained.

n designates another finger connected with the stop-bar which extends forward over the free end of a lever *o*, which, when depressed as it will be by the finger *n* when the stop-bar is rocked forward, will operate the dogs so as to allow the carriage to shift or be shifted.

p is the tabulating key-lever which at its front end extends through the front plate of the machine and is provided with a key *q*, and at its rear end has a loose connection with a finger *r* projecting from the stop-bar. At an intermediate point the lever *p* is vertically and horizontally pivoted upon a bracket *s* or other part of the frame so that

the key end of the said lever can be depressed and moved horizontally, operating the rear end of the lever in the same manner, and through its connections with the 5 stop-bar rocking it on its journal pins and moving it longitudinally.

10 *t* is a plate adapted to be secured to the front plate of the machine, and having a scale *u* inscribed thereon, which scale coördinates, so far as it goes, with the cylinder scale. The forward end of the tabulating key-lever *p* projects through the scale plate *t*, and is provided with a pointer *v* projecting in close proximity to the scale.

15 The tabulating key-lever *p* is shown as bent or crooked, but the form shown is given to it merely to keep it out of the way of other parts of a machine to which it may be applied. It would perform its functions as 20 well if it were made straight or of other shape than that shown.

With this description of the construction and arrangement of the invention and parts with which it is related, a brief description 25 of the mode of operation will be given: The stops *j* on the stop-bar when brought within the path of travel of an abutment or projection *w* of the carriage will arrest the travel or shifting movement of the carriage. 30 Hence, if columns of figures of a table are to be written, the stop will be set on the line where, say, the period dividing the cents from the dollars will occur. Under this arrangement the entire extent to which the 35 stops may be shifted or adjusted may be utilized for writing figures designating dollars, and inserting commas dividing the hundreds from the thousands and the latter from the millions. If the smallest amount 40 is to be written (say, cents only,) the stop-key will be simply depressed which will not shift or adjust the stop-bar, but release the carriage and allow it to run forward until it is arrested by the stop in normal position, 45 which will be on the line of the periods, as before stated. If the largest amount to be written is ten million, as indicated in the drawings, the operator by shifting the key *q* to the left will move the stop-bar to adjust 50 the stop so that it will arrest the carriage ten points in advance of the point upon which it would normally be arrested, or at exactly the point where the writing of ten million should begin. Supposing again the maximum amount in a table to be 10,000,000, as 55 is inscribed on the scale *u*, and that in one line it is proposed to write 10,000, the operator by shifting the key *q* and moving it and the outer end of the lever *p* to the left six 60 degrees of the scale *u*, will shift the stop-bar *b* and stop *j* correspondingly, causing the shifting movement of the carriage to be arrested exactly on the line where the writing of ten thousand is to be begun. The finger 65 *m* having engaged the teeth of the rack-bar

70 *l* will assist in supporting the stop-bar *b* against the slamming action of the carriage on being arrested in its shifting movement by the stop.

75 It will be seen that with this invention, the stop *j* will be set to arrest the carriage in its shifting movement at that line in the column where the period dividing the cents from the dollars is to be written, by depressing the tabulating key *q*. By shifting this key to the left, the lever *p* will be operated to adjust the stop *j* on the stop bar *b* to the right so as to stop the carriage at any desired point from the period to the ten million line. Of course, as indicated in Fig. 1 of the drawings, more than one step may be employed 80 on the stop bar to arrest the shifting traverse of the carriage at different points when more than one table or other column of work is to be written, just as has been done heretofore in tabulating devices.

85 From the foregoing description it will be seen that the stop bar constitutes a movable carrier upon which the adjustable stop or stops are mounted and that a movement of 90 the stop bar or carrier in the line of the movement of the carriage will determine the point or points at which the carriage is to be stopped and that this movement of the stop or stops with the carrier in no way affects 95 the adjustment of the stop or stops with respect to the carrier.

98 By the use of my invention much time and trouble is saved in shifting the carriage for the reason that the carriage is stopped with 100 certainty at exactly the point at which the writing is to begin without jumping the carriage forward from the extreme limit to the said point. Moreover, the operator is not obliged to make special observation of the 105 position of the carriage with respect to the cylinder scale.

110 The special and important feature of my invention is the stop key lever which is engaged with and shifts or adjusts the stop bar and stops for the purpose explained whatever may be the form or arrangement of the parts mentioned.

115 It will be apparent that the key lever *p*, when depressed by the operator will cause the stop-carrying bar *b* to be turned so as to bring the finger *m* into engagement with the rack *l*; the finger and rack by their engagement are adapted to receive the impact which is transmitted to the bar *b* when the abutment stop *w* collides with the column stop *j* upon the release of the carriage, and thus a longitudinal displacement of the bar *b* and of the carriage, after the two stops have come into engagement, is positively prevented, and the stop *j* is held immovable in the position to which it has been adjusted by the lateral movement of the key *q*. The same function of holding the stop *j* (and the carriage, when it jumps into contact with 120

125 the finger *m*) having engaged the teeth of the rack-bar

said stop) against longitudinal movement, is also effected by the engagement of the key lever *p* between two of the teeth shown at the lower portion of the plate *t*. There is thus a double security against the longitudinal movement of the bar *b* under the impact of the carriage, and these two holding or retaining means are connected with the bar *b* at opposite sides of the point of impact (the stop *j*), so that the structure is exceedingly rigid. The key lever *p*, therefore, not only serves to adjust the stop *j*, but also, by coöperating with the teeth on the plate *t*, as described, assists in maintaining the bar *b* and the stop *j* in the adjusted position as long as the operator holds the key *q* down. At the same time, the lever *p* in connection with the bar *b*, the finger *n* and the lever *o* forms means for actuating the release mechanism of the carriage. Further, the sides of the recess in the upper portion of the plate *t* serve to mechanically limit the adjustment or throw of the lever *p* and consequently of the stop also. Finally, it will be understood that the stop *j* is held on the bar *b* by means of a toothed spring-pressed finger *j'*, which forms an independently mounted spring-pressed device for locking the stop in position on the bar.

By reason of the pressure of the spring *f* the key *q* will normally remain in the extreme right hand position in the recess in the plate *t*, which position is indicated by the decimal point on the scale *u*, with which the plate *t* is provided. The key *q* is provided with a pointer *v*, and this pointer *v* in connection with the scale *u* may be termed a "selecting device", because by its aid the operator is enabled to select the proper column in which to write the first figure of the desired number. The lower part of the recess in the plate *t*, as above stated, is provided with a series of teeth so placed that the spaces or notches between them come directly under the divisions of the scale *u*. In order to adjust the position of the column stop *j*, the key *q* is first moved horizontally to the left until the pointer *v* coöperating with the scale *u* indicates the column in which the first figure of the desired number is to be written. This movement produces a corresponding movement of the stop bar *b*, and of the stop *j* upon it. The key *q* is then depressed for the purpose of moving the column stop *j* into the path of the stop *w* upon the carriage, which stop *w* is termed the "denomination stop". Upon depressing the key *q*, it will enter the space between the teeth on the plate *t* corresponding to the division on the scale *u* indicated by the pointer *v*, and will be thereby detained or prevented from moving sideways, and with it also the stop bar *b* and the column stop *j*, as long as the key *q* is depressed. At the same time, the finger or

detent *m* will engage with one of the teeth of the rack *l* and detain the stop *j* in a similar manner and thus coöperate with the key *q*, when in engagement with one of the notches of the plate *t*, in notwithstanding the impact of the moving denomination stop *w*. The carriage will thereby be arrested in the desired working position, and the carriage spring will keep the denomination stop *w* in contact with the stop *j* and in the working position, until the key *q* is released. Upon depressing the key *q* the escapement will be released automatically from the carriage, and on releasing the key *q*, the escapement will again engage and retain the carriage in the desired working position. The tabulating mechanism will then disengage from the carriage and return automatically to its initial position.

Since the adjustable bar of my device is entirely free from and independent of the carriage, it is obvious that my attachment can be applied to any of the leading types of machines, whether they have a hinged carriage or whether, as in the case of the Smith Premier machine, the sliding carriage has no hinged movement.

Having described my invention, what I claim and desire to secure by Letters Patent is:

1. The combination with the carriage and the release mechanism therefor, of a vertically and laterally movable stop key lever and a bar equipped with a column stop and connected with said stop-key lever, said bar being adapted to be moved longitudinally as the stop key lever is moved laterally and to be rocked as the said stop-key lever is moved vertically so that said lever will operate to both set the stop at any predetermined position and to swing the bar to release the carriage.

2. The combination, with the longitudinally adjustable stop bar, of a single stop key lever for moving the stop bar in two directions and into operative position to arrest the carriage, and means for returning the stop bar to its normal position when the stop-key lever is released, substantially as described.

3. A tabulating device for a typewriter comprising a longitudinally adjustable stop bar mounted to move on stationary bearings secured to the frame of the machine and provided with means for engaging a stop on the carriage to arrest the movement of the carriage, and lever carried by the framing of the machine for shifting the stop bar longitudinally and to bring it into operative position in order to stop the carriage at any predetermined point, substantially as described.

4. The combination of an adjustable stop bar mounted in bearings on the frame of the machine and provided with a stop adapted to engage a corresponding stop on the carriage, a lever for actuating said stop bar, a toothed bar

secured to the frame, and a finger projecting from the stop bar so as to engage said toothed bar when the stop bar is in operative position, thus holding the stop bar firmly against 5 the impact of the carriage, substantially as described.

5. A tabulating attachment for a typewriter comprising a stop-bar having a longitudinal and a rocking movement on its bearings, a stop secured to said stop bar and adapted to engage a stop on the carriage, a lever having operative engagement with said stop bar and serving both to move the bar longitudinally and to rock the same, and a 10 finger secured to the stop bar and adapted to be moved into engagement with a toothed bar on the frame when the stop bar is rocked into operative position.

6. In a tabulating device for a typewriter 20 the combination of the longitudinally adjustable stop bar adapted to be rocked on its bearings, a stop secured to said bar and adapted to engage a corresponding stop on the carriage, and a lever for actuating the 25 stop bar, said lever operating to simultaneously release the carriage and move the stop bar into operative position to arrest the movement of the carriage at a predetermined point, substantially as described.

30 7. In a tabulating device for typewriting machines, the combination of a movable carrier, an adjustable stop carried thereby, a second stop coöperating therewith to limit the movement of the carriage and a single 35 hand-operated key for moving the movable carrier in the line of the feed of the carriage without changing the adjustment of said adjustable stop with respect to its carrier and for moving the adjustable stop into position 40 to arrest the carriage, whereby an operation of the single hand operated key may effect the arrest of the carriage at a point determined by the positioning of the movable carrier in the line of the feed of the carriage.

45 8. In a tabulating device for typewriting machines, the combination of a movable carrier, an adjustable stop carried thereby, a second stop coöperating therewith to limit the movement of the carriage, a single hand 50 operated lever for moving the movable carrier in the line of the feed of the carriage without changing the adjustment of said adjustable stop with respect to its carrier and for moving the adjustable stop into position 55 to arrest the carriage, whereby an operation of the single hand-operated lever may effect the arrest of the carriage at a point determined by the positioning of the movable carrier in the line of the feed of the carriage, and 60 means controlled by said single lever for automatically releasing the carriage when the tabulating device is operated.

9. In a tabulating device for typewriting machines, the combination of a movable carrier, an adjustable stop carried thereby, a

second stop coöperating therewith to limit the movement of the carriage, means for moving the movable carrier in the line of the feed of the carriage without changing the adjustment of said adjustable stop with respect to its carrier and for moving the adjustable stop into position to arrest the carriage, whereby when the movable carrier is operated, the carriage will be arrested at a point determined by the positioning of the 70 movable carrier, means for releasing the carriage when the said carrier is operated and means for preventing displacement of the movable carrier in the direction of the feed of the carriage when the adjustable stop has 75 been moved to arrest the carriage.

10. In a tabulating attachment for typewriting machines of the traveling paper carriage class, the combination of a toothed stop bar movable in one direction and adjustable in another direction, a paper carriage stop upon said toothed stop bar, a single key operated mechanism which serves for adjusting the toothed stop bar as well as for moving it with the stop, and an abutment carried by the paper carriage and so placed as to make contact with the paper carriage stop when the paper carriage is 80 lineally advanced by means other than its 85 normal step by step feed mechanism. 90

11. In a tabulating attachment for typewriting machines of the traveling paper carriage class, the combination of a toothed stop bar adjustable longitudinally, a paper carriage stop upon said toothed stop bar, the 100 toothed stop bar and stop being further movable in unison so as to throw the stop transversely, a single key operated mechanism for adjusting the toothed stop bar and for moving it so as to throw the stop transversely, and 105 an abutment carried by the paper carriage and so placed as to make contact with the paper carriage stop when the paper carriage is lineally advanced by means other than its normal step by step feed mechanism. 110

12. In a tabulating attachment for typewriting machines, a stop device having means for arresting the carriage at variable points, an operating lever or handle having an operative connection with said stop device, and two devices rigidly connected with each other and each operative while the said operating lever is depressed, the one to hold the stop device against lateral movement and the other to actuate the carriage-releasing 115 mechanism. 120

13. In a tabulating attachment for typewriting machines, a stop device having means for arresting the carriage at variable points, operating means for said stop device, 125 a finger rigidly connected with the stop device, and arranged for locking engagement with a stationary part when the said operating means is actuated, and a device for actuating the carriage-release mechanism, said 130

device being also rigidly connected with the stop device.

14. In a tabulating attachment for typewriting machines, an adjustable stop device 5 for arresting the carriage at different distances from a predetermined point, a carriage-release mechanism directly connected with said stop device, mechanism also positively connected with said stop device for 10 preventing a change of adjustment of the stop device while the same is held in its working position, and a single operating means for actuating said stop device and for bringing the carriage release mechanism 15 and the means for preventing a change of adjustment of the stop device into action simultaneously with the movement of the stop device into its working position.

15. In a typewriting and tabulating mechanism, the combination of a carriage, a series of independently adjustable column stops, said stops being also movable transversely to be brought into and out of the path of a part on the carriage, a lever 25 connected to said stops to adjust them simultaneously to different denominational positions independently of the carriage and to move them transversely, and means for mechanically limiting the extent of adjustment of said lever and said stops.

16. In a typewriting and tabulating mechanism, the combination of the carriage, an abutment, a series of column stops arranged to move transversely to coöperate with said 35 abutment, the column stops being also adjustable in the direction of the carriage-feed, a single key for adjusting the column stops and for moving them transversely, and a device operating as long as the key is 40 depressed to hold said column stops against movement in the line of the carriage-feed.

17. In a typewriting and tabulating mechanism, the combination of a power-driven carriage, escapement devices, carriage releasing mechanism, an abutment, a series of column stops constructed to move transversely 45 for engaging said abutment, means for moving said column stops transversely and simultaneously operating said carriage-releasing mechanism, and means operatively connected with the first-named means for holding the said column stops and said carriage-releasing mechanism against movement in the line of the carriage-feed as long as the 50 operator actuates said first-named means.

18. In a typewriting and tabulating mechanism, the combination of a power-driven carriage, escapement devices, a carriage-releasing mechanism, a bar mounted to move 55 parallel with said carriage and carrying a series of independently adjustable column stops, devices operated by a single key and mounted upon the frame-work of the machine, said devices being operatively con-

nected to said column stop bar and said releasing-mechanism, and means operative as long as the key is depressed for holding said column stop bar and said releasing-mechanism against movement in the line of the carriage-feed.

19. In a typewriting and tabulating mechanism, the combination of the carriage, an abutment, a series of column stops, adjustable lengthwise and movable transversely, a single key for moving the column stops 70 transversely to engage the abutment and for adjusting them lengthwise, and devices operating when said key is depressed to hold said column stops against movement in the line of the carriage-feed and to allow said stops to return to their normal position upon the release of said key.

20. In a typewriting and tabulating mechanism, the combination of a power-driven carriage, escapement devices, carriage-releasing mechanism, an abutment and a column stop, one of the two last named elements being adjustable lengthwise in unison with the carriage release mechanism and movable transversely to a position for engagement with the other element, a single key for adjusting said element and for moving it transversely and for simultaneously operating the carriage-releasing mechanism, and means operated by the depression and 90 subsequent release of said key to first hold the said movable element and the carriage-release mechanism against movement in the line of the carriage feed, and then to enable the said parts to return to their normal position.

21. The combination of the carriage, a longitudinally adjustable bar, a stop carried by said bar and movable transversely of the carriage path, means for adjusting the bar 105 endwise in a direction parallel with the run of the carriage and for moving the stop transversely, and means operating upon the actuation of the first-named means for preventing a change of adjustment of the said bar.

22. The combination of a carriage, a bar adjustable endwise, a stop carried by said bar and movable transversely, a key for moving said bar endwise in a direction parallel with the run of the carriage and for 115 moving the stop transversely, mechanism brought into action by the depression of said key, for holding said bar against endwise movement, and means operating automatically upon the release of the key, to free 120 the said bar from the control of said mechanism.

23. In a typewriting and tabulating mechanism, the combination with a longitudinally adjustable bar, a column stop carried 125 by and adjustable along said bar, said stop being also movable transversely of the carriage path, and a key for adjusting the bar

and moving the stop transversely, of an independently mounted spring pressed device for locking said stop in position upon said bar.

5 24. The combination of the carriage, a bar movable lengthwise, a stop carried by said bar and movable transversely of the carriage path, two devices for preventing the lengthwise movement of said bar when the stop 10 has been moved transversely to its working position, said devices being located at opposite sides of the stop, and means for actuating said stop.

25. The combination with the frame and 15 the carriage of two racks arranged at the front portion and at the rear portion of the frame respectively, a tabulating key located adjacent to the front rack and movable both lengthwise and transversely thereof, to engage it at different points, and a tabulating stop, for arresting the carriage, operatively connected with said key and connected with a projection movable both lengthwise and transversely of the rear rack to engage the 25 same.

26. The combination with the frame and carriage, of two racks arranged at the front portion and at the rear portion of the frame respectively, a tabulating key located adjacent to the front rack and movable both lengthwise and transversely thereof, to engage it at different points, and a tabulating stop, for arresting the carriage, operatively connected with said key to move lengthwise 30 in the opposite direction to said key and transversely in the same direction as the key, said tabulating stop being connected with a 35

projection located adjacent to the rear rack and adapted to engage it at different points.

27. The combination with the frame and 40 the carriage, of two racks arranged at the front portion and at the rear portion of the frame respectively and extending parallel to the path of the carriage, a tabulating key universally pivoted on the frame at a point 45 forward of the rear rack and rearward of the front rack, the front portion of the key moving adjacent to the front rack and being adapted to engage it at different points, and a tabulating stop, for arresting the carriage, 50 operatively connected with the rear portion of the key and connected with a projection movable both lengthwise and transversely of the rear rack to engage the same at different points. 55

28. The combination, with the frame and the carriage, of a tabulating stop movable transversely of the carriage path to arrest the same, and also movable lengthwise of the carriage path to different positions, means 60 for operating said stop, and a stationary rack arranged lengthwise of the carriage path and adapted to be engaged at different points by a projection connected with the stop to brace said stop against the impact of the carriage. 65

In testimony whereof I have signed my name to this specification, in the presence of two subscribing witnesses, this 17th day of February A. D. 1899.

J FRANK ALLARD.
